(57) **CLAIM**

The ornamental design for a capsule, as shown and described.

DESCRIPTION

1. Capsule

1.1 : Perspective

1.2 : Left

1.3 : Right

1.4 : Front

1.5 : Back

1.6 : Top

1.7 : Bottom

Fig. 1.1 is a perspective view of the design; fig. 1.2 is a left view thereof; fig. 1.3 is a right view thereof; fig. 1.4 is a front view thereof; fig. 1.5 is a rear view thereof; fig. 1.6 is a top view thereof; fig. 1.7 is a bottom view thereof; the name of the claimed design product is capsule to be used for the preparation of a beverage; the relevant feature of the design product is the shape; the figure that shows better the main points of the design is the perspective view. The broken lines in the figures illustrate the portions of the capsule that form no part of the claimed design.
